[57] CLAIM

The ornamental design for a pair of insulating sheaths for tong handles, as shown and described.

DESCRIPTION

FIG. 1 is a front elevational view of one of the pair of insulating sheaths for tong handles showing my new design;

FIG. 2 is a side elevational view thereof;

FIG. 3 is a cross-sectional view thereof, taken along the line 3—3 of FIG. 1;

FIG. 4 is an enlarged perspective view of the pair of insulating sheaths for tong handles showing my new design in the molded position, conforming to a tong handle.

The other insulating sheath has been omitted from FIGS. 1-3 for convenience of illustration only.
